HAT

Philip E. Young, Arcadia, Calif., assignor to George S. Bailey Hat Company, Los Angeles, Calif., a corporation of California

Application July 20, 1953, Serial No. 26,045

Term of patent 14 years

(Cl. D3—13)

To all whom it may concern:

Be it known that I, Philip E. Young, a citizen of the United States, residing at Arcadia, in the county of Los Angeles and State of California, have invented a new, original, and ornamental Design for a Hat, of which the following is a specification, reference being had to the accompanying drawing forming a part thereof.

Fig. 1 is a top perspective view of a hat, showing my new design;

Fig. 2 is a top plan view of the hat shown in Fig. 1;

Fig. 3 is a fragmentary sectional view taken on line 3-3 of Fig. 2; and

Fig. 4 is a fragmentary sectional view thereof, taken on line 4-4 of Fig. 2.

The essential features of my design reside in the portions shown in solid lines on the drawing.

I claim:

The ornamental design for a hat, as shown and described.
